UNITED STATES PATENT OFFICE.

JOHN C. SILSBY, OF NEWPORT, NEW HAMPSHIRE.

COCK.

No. 797,234.

Specification of Letters Patent.

Patented Aug. 15, 1905.

Application filed November 10, 1902, Serial No. 130,666.

To all whom it may concern:

Be it known that I, JOHN C. SILSBY, of Newport, in the county of Sullivan and State of New Hampshire, have invented certain new and useful Improvements in Cocks, of which the following is a specification.

My present invention relates to cocks or valves, and is herein illustrated as applied to what is called a "stop" and "waste" cock.

The principal points of my present invention consist in so forming the several parts making up the whole article, that the inner shell and connecting-valves and appurtenances may be readily removed from the outer shell; the arrangement and peculiarities of the stop and the waste valves to a common stem; the direct downward exit for the waste water, and certain other improvements hereinafter set forth.

In the drawings, Figure 1 represents a sectional elevation of the cock set in place in the ground. Fig. 2 is an elevation of the inner shell removed from the outer or main shell.

In the drawings, H represents the main or outer shell secured to pipes at either side as being used for an ordinary water-hydrant cock or as an ordinary stop and waste cock in a street line of pipe, h being the opening for the entrance of the water and k the outlet. Near the lower end of the said shell is formed an internal screw-thread e', which coincides with the threaded end of the inner shell near its bottom, as indicated by e. The engagement of the parts by this screw-thread serves to hold the outer and inner shells together. The inner shell proper is represented by D, and which is provided with openings for the entrance and the exit of the water, coinciding with the similar openings formed in the shell H. In Fig. 1 the several parts are shown as in place with the stop-valve closed and the waste-valve open.

A is the stem, which extends from the top to nearly the bottom of the cock and which carries the stop-valve a, shown as seated on its seat a', and the waste-valve F, secured to the lower end of the stem and adapted to be seated at E' by the raising of the stem. The circular top plug C is secured to the inner shell D by the screw-thread c and the top nut B to the top plug C by the screw-thread b. The stem passes through the nut B and is screw-threaded d d' to the inner part of plug C. The wrench is applied to the top A' of the stem and when turned of course raises

or lowers the stem and the valves attached to the stem. The outside of the inner shell D is made to fit closely to the interior of the body of the shell H. The top of the shell D is formed like a nut d², Fig. 2, so that by applying to the nut part d² of the inner shell C the usual extension-wrench through the box A², which extends from the cock to the surface of the ground, the whole shell C, with all its contents, may be easily unscrewed from the shell H and removed therefrom for repair or other causes. I preferably remove a part of the stem A where it passes through the waste-valve section E², as indicated by E. The object of this is to facilitate the flow of water when the waste-valve is open. When the stem is raised in the act of opening the stop-valve, the lower part of the stem a² will substantially close the waste-valve-section opening E², and thus prevent the water from the stop-valve when entering from escaping by the waste-valve-section opening.

It is desirable to have a ready means of removing the valve parts for purposes of repair or other causes from the main shell H of the cock. The cock is often buried to a considerable depth in the earth and secured each side to the main system of pipes. It will be observed that by my form of parts the inner shell can be readily removed from the outer shell while the latter is connected to the water-pipes in the ground without removing any earth or disturbing the permanent structure.

In operation, the stop-valve a being raised, the water enters the cock at h and passes downward through the valve-opening and out at k, the waste-valve F being closed by the act of raising the stem A in opening the stop-valve a. When the stem is screwed down, the valve a is closed, and the waste-valve F is opened, and the waste water is removed downward through the bottom or lower end of the cock.

All parts of the cock are simple, easily made, and durable. In operation they would not be likely to get out of order or prove ineffective in practical use.

I do not confine myself to the special form of parts shown or to the special application of the cock to the use illustrated, as the principles of my invention may be varied in form and differently attached in use without departing from the spirit of my improvements as described. For instance, the two shells may be removably secured together by dif-

ferent means, the arrangement for substantially closing the waste-opening while the stop-valve is being opened or closed may be varied, and other similar changes made as to details.

Having now explained my invention, what I desire to claim and secure by Letters Patent of the United States is—

1. A cock formed of the main shell H and an inner shell D, each provided with the apertures h and k; the shell D having the vertically-moving stem A, and the valves a and F, each secured to said stem, and the valve-seats a' and E' forming a part of the shell D; the depression E, in the stem, and the opening E², of the valve-seat opening E'; the top nut B, and the top plug C, adapted to be screwed to the shell D; the shell D, adapted to be removably screwed to the main shell H, all combined and adapted to operate, substantially as and for the purposes set forth.

2. A stop and waste cock, formed with an outer and an inner shell, removably screwed together, the inner shell carrying the vertically-operative spindle A, the valves a and F; valve-seats a' and E' with connecting

parts and all combined and adapted to operate substantially as set forth.

3. In a cock, the combination of the outer or main shell H, and the inner shell D, carrying therein a vertically reciprocating valve mechanism consisting of a stop-valve and a waste-valve, each having a valve-seat, formed with the inner shell, the two shells being internally screw-threaded together, so that the inner shell may readily be removed from the top, all substantially as set forth.

4. In a cock, a main or outer shell, provided with an interior screw-thread; a secondary or inner shell, provided with an exterior screw-thread, and also having two valve-seats, each inclosing annular openings; and a vertically-movable stem, having two valves secured thereto, and all combined and adapted to operate substantially as set forth.

In testimony whereof I have affixed my signature in presence of two witnesses.

JOHN C. SILSBY.
